METALLIC WINDOW FRAME AND SASH

Filed Oct. 31, 1929

INVENTOR
HENRY C. HASSELBUSCH
BY Edward E. Longan
ATTORNEY.

UNITED STATES PATENT OFFICE

HENRY C. HASSELBUSCH, OF ST. LOUIS, MISSOURI

METALLIC WINDOW FRAME AND SASH

Application filed October 31, 1929. Serial No. 403,702.

My invention relates to improvements in metallic window frames and sashes, and has for its primary object a window frame and sash composed of metal strips, which sash is pivoted in the frame intermediate its top and bottom in such a manner that it will be self closing.

A further object is to construct a metallic window frame and sash in which the sash is pivotally mounted at its sides in the frame so as to be self closing and automatically locked so that it cannot be opened from the outside without breaking the glass in the sash.

15 A still further object is to construct a window frame having a sash pivoted therein so that the sash will be self closing, the sash being provided with a latch or lock for holding it in closed position, the latch being opened by a flexible member which will also swing the sash on its pivots thereby opening the window and which can be so secured as to hold the window in open position.

25 A still further object is to construct a metallic window frame and sash, the frame and sash having pivots on opposite sides, which pivots are removably held in position by certain portions of the frame and sash, so that no rivets or screws are required, and when once assembled in position in the frame can not become loose accidentally or be removed without taking the frame apart.

Heretofore, as far as I have been able to ascertain, when metallic window frames and sashes were used, hinges or pivots, which were secured by means of rivets or screws, were employed. These hinges or pivots were naturally more or less fragile and it frequently happened that the same became broken but by my construction I have devised a sturdy pivot which does not require any extraneous fastening means to hold it in place and which is practically unbreakable, and at the same time is so positioned that there is little danger of corrosion so that the pivot will be freely working at all times.

In the drawings:

Fig. 1 is an inside view of a window frame and sash with parts broken away.

showing the arrangement of my construction.

Fig. 2 is a section taken on the line 2—2 of Fig. 1 viewed in the direction of the arrow.

55 Fig. 3 is a section taken on the line 3—3 of Fig. 1 viewed in the direction of the arrow.

Fig. 4 is a fragmental section taken on the line 4—4 of Fig. 1.

60 Fig. 5 is a modified form of means for holding the window in open position.

Fig. 6 is an enlarged face view of one of the pivot members; and

Fig. 7 is an enlarged section of a pair of 65 pivot members in assembled position.

In the construction of my device I employ a window sash composed of rails 8 and 9 and stiles 10 and 11. The rails and stiles are constructed of metal, preferably in the form of 70 an X. 12 represents the glass in the sash. The sash may be provided with an intermediate bar 13, which is of the same cross section as the rails and stiles. This is done in order to obviate the necessity of using large 75 panes of glass.

The frame is composed of a top member 14, a bottom member 15, and side members 16 and 17, the cross section of these last mentioned members being identical with the stiles and 80 rails of the sash.

The side members 16 and 17 have inwardly projecting flanges or ribs 18, which are cut away intermediate their ends so as to leave a gap (see Fig. 3) and in this gap is placed 85 a cylindrical pivot member 19, which is provided with recesses or slots 20 in their peripheries so as to receive a portion of the ribs 18. This is clearly illustrated in Fig. 3.

The cylindrical members 19 are provided 90 with central bores 21, which are adapted to receive a cylindrical pin 22. The stiles 10 and 11 also have projecting ribs 23, which have a gap formed therein as illustrated in Fig. 2 and in which gap a cylindrical pivot 95 member 24 is placed, this cylindrical member being of the identical construction as the member 19. The members 24 are also provided with a bore 25 into which the pin 22 extends.

Secured to the rib 26, which is formed integral with the top member 14 and to the ribs 18 of the side members 16 and 17 of the frame, are metallic plates 27 and 28. The plates 27 extend entirely across the frame, while the plates 28 only extend down to the pivot members 19 (see Fig. 2).

The flanges 23 of the rails 10 and 11 and the flange 29 of the lower stile of the sash are also provided with plates 30, these plates being located on the opposite side so that when the sash is closed, the upper portion of the sash will rest against the plates 27 and 28 while the plates 30 secured to the sash below the pivot members 24 will contact with the rib 26 thus making a weather-proof joint. This construction is essential because as the window is swung on its pivots the lower portion moves outward and the upper portion inward and it is for this reason that the portion of the sash below the pivot point must carry the plates or weather stripping as it may be termed, while the frame above the pivot points carries the remaining plates or weather stripping. If this were not done, it would be impossible to open the window.

The lower rail 9 of the sash carries a spring latch or lock 31, which passes through an opening 32 formed in the bottom member of the frame. This latch has attached thereto a chain or flexible member 33, which passes upward and over a roller carried by a yoke 34, which yoke is attached to the top stile of the sash. The free end of the flexible member 33 extends downward and is preferably provided at its lower end with a ring 35 so that when this ring is grasped a pull can be exerted on the chain or flexible member 33, first lifting the latch out of its socket and releasing the window, and then continued pulling will cause a pull to be exerted on the upper portion of the window swinging it inward. The ring 35 can then be hooked over the projection carried either by the window frame or by the wall of the building thus holding the window in open position.

It will be noted from Fig. 1 that the pivot points of the sash are above the center so that the lower portion will be of greater length than the upper portion. Consequently when the ring is released from its retaining means and the flexible member released by the operator the window will swing to closed position by its own inertia or weight due to the fact that the lower portion overbalances the top portion and will then automatically lock.

The form of window thus described is preferably used for windows which are at a considerable distance above the floor. Where the windows are close to the floor I may dispense with the flexible means and instead pivot a toothed bar 36 to the window sash, the notches of this toothed bar being spaced apart so that by pushing out on the bar or

sash the opening of a window can be regulated and it can be readily held in open position at any predetermined angle by means of the notches or teeth 37 of the bar engaging with the window frame.

It will be noted that in the construction of my device that the sash is either welded or riveted so as to form an integral structure while the frame has the top and bottom members and one side member similarly secured, the remaining side member being left unsecured for assembling purposes, and after such assembly this remaining member is secured in position by riveting or by means of screws.

Having fully described my invention, what I claim is:

1. A device of the class described comprising a metallic sash and frame each provided with longitudinal ribs extending toward each other and abutting along their edges, said ribs having gaps formed therein opposite each other, cylindrical members removably insertable into said gaps, each member having diametrically opposite slots, and a central bore located in said gaps, said ribs slidably entering said slots for holding said cylindrical members in position in said gaps and against rotation, and a pin removably projecting into the central bore of adjacent cylindrical members.

2. The device of claim 1 in which the sash is provided with means whereby the same can be readily opened and held in open position and in which the cylindrical members are disposed above the center of the window sash so that said sash will close by gravity when the opening means is released.

3. The combination of a metallic supporting window frame formed with inwardly projecting ribs on opposite sides of the frame, a window sash provided with outwardly projecting ribs arranged to lie in close edge to edge relation to the ribs of the supporting frame, the two sets of ribs being cut away intermediate their ends to leave gaps, which are arranged opposite each other and in line, bearings slidably seated in the said gaps and pins detachably mounted in the said bearings and pivotally uniting the sash with the frame so it may swing therein.

4. The combination stated in claim 3, including also plates carried respectively by the supporting frame and the window sash for covering the joints formed by the opposing edges of the ribs.

In testimony whereof I have affixed my signature.

HENRY C. HASSELBUSCH.
